RAILWAY SWITCH STAND

Filed March 13, 1928

Patented May 21, 1929.

UNITED STATES PATENT OFFICE.

EUGENE F. SALISBURY, OF MINDEN, LOUISIANA.

RAILWAY-SWITCH STAND.

Application filed March 13, 1928. Serial No. 261,322.

This invention relates to railway switch stands and locking devices therefor.

One object of the present invention is to provide a railway switch point operating mechanism wherein the locking mechanism for holding the switch points against accidental operation is housed separately from the switch stand, the housing for such locking mechanism being comparatively low and resting on top of the head blocks which support the switch stand. By having the locking mechanism in a small low housing, preferably located between the head blocks, there is little likelihood of the connecting rod and switch points being injured or accidentally operated by timbers or other heavy objects falling from passing cars. This is not necessarily true in those types of structures wherein the locking mechanism is housed in the switch stand which rises a considerable distance above the head blocks and is likely to be destroyed or knocked down by timbers or other heavy objects falling from passing cars.

25 A further object is to provide a switch point operating mechanism having the target rod supported in the switch stand, but normally disengaged from the connecting rod which is attached to the switch points.

30 With this arrangement, if the switch stand is knocked down or demolished by heavy objects falling from the passing cars, it will not effect, in any way, the connecting rod or the switch points, the latter remaining in whichever position they happen to be locked in at that time.

With these and other objects in view the invention consists of certain novel details of construction and combinations and arrangements of parts, all as will hereinafter be more fully described and the novel features thereof particularly pointed out in the appended claims.

In the accompanying drawings,

45 Figure 1 is a plan view illustrating the head blocks, a portion of the rails and switch points, and the mechanism for operating the connecting rod which is attached to the switch points.

50 Fig. 2 is an elevational view of the switch stand, the head blocks being shown in section.

55 Fig. 3 is a sectional view taken transversely of the head blocks and illustrating the locking mechanism for the connecting rod.

Fig. 4 is an enlarged perspective view of the upper portion of the switch stand; and

Fig. 5 is a vertical sectional view through that portion of the apparatus shown in Fig. 4.

As is usual, the switch points 10 are adapted to be moved into either of their desired positions through a connecting rod 11. In the present construction this connecting rod 65 lies between the two head blocks 12 and preferably below the upper surface of the latter, its free end remote from the switch points being slidably received in a supported casing formed on the inner surface of a plate 14 attached to and spanning the two head blocks. Normally, the free end of connecting rod 11 is disengaged from the target rod to be later described and for this reason means are provided for engaging the connecting rod and locking it against accidental actuation. The preferred locking means consist of a lever 15 pivoted on plate 14 and provided with a depending bifurcated end portion 16, the bifurcations being adapted 70 to engage in recesses 17 formed in the connecting rod. As will be apparent when the bifurcations are in engagement with the connecting rod the latter will be held against movement, but the desired pressure of the operator's foot on one end of the lever 15 will elevate the bifurcations at the opposite 75 end thereby freeing the connecting rod.

For locking the lever with the bifurcations in engagement with the connecting rod so 80 as to prevent tampering therewith by unauthorized persons, a padlock may be utilized, the lever having an apertured projecting portion 18 and there being a similar projection 19 on plate 14 to which the lock, illustrated diagrammatically at 20 in Fig. 1, 85 may be applied.

As has been before stated, the present invention contemplates an actuating mechanism wherein the target rod is normally disconnected from the connecting rod. For this purpose the target rod 21 is slidably received in a rotatable member 22 rotatably mounted on the locking plate 23 of the switch stand 24, the base of the latter being 100 permanently mounted on the block heads 12. Pivoted at 25 in member 22 is the operating lever 26 which normally assumes a depending position so as to be held by plate 23 105 against movement around the longitudinal center of the target rod. In order that lever 26 may assume such depending position,

member 22 is slotted as at 27 and locking plate 23 is also cut away. The end of lever 26 engaging the target rod is formed with bifurcations 28 and is rounded as at 29 so as to enter recesses 30 formed in the target body. The target body being slidably mounted in the switch stand it will be apparent that movement of the lever 26 to its depending position will result in elevating the target rod, that elevated position of said rod being such that its crank shaped lever end portion 21^a is raised above and disengaged from the connecting rod 11. With the parts in this, their normal position, not only will the target rod be disengaged from the connecting rod, but the lever 26, being in its depended position, will hold the target rod against rotation so that the target signal will still serve the purpose of indicating the position of the switch point.

However, if it is desired to actuate the switch points, lever 26 is elevated by turning on its pivot 25, whereupon the bifurcated end portion of said lever will depress target rod 21, moving it into engagement with the connecting rod. This upward movement of the lever 26 brings it to substantially a horizontal position and, being free of locking plate 23, it, together with member 22 and the target rod 21, may be rotated, and the connecting rod having been engaged by the target rod the switch points may be thrown, it being understood that preparatory to actuation of the mechanism, the locking means heretofore desired have been disengaged from the connecting rod so as to free the latter.

By having the switch stand, together with the operating lever, and target rod, normally disassociated, so to speak, from the connecting rod it will be appreciated that interference with, or absolute destruction of, the switch stand by timbers or other heavy objects falling from passing cars will have absolutely no effect on the switch points, nor even on the connecting rod. Likewise, by having the connecting rod located below the upper surfaces of the head blocks and by having the locking mechanism therefor substantially housed below the surface of the head blocks there is little, if any, danger of injury to such locking mechanism by falling timbers. Preferably, the reciprocation of the target rod into and out of engagement with the connecting rod is effected by the operating lever with which the target rod is also rotated. This simplifies the construction considerably as compared with the provision of separate actuating means, that is, one means for reciprocating the target rod and another for rotating it.

However, as the present invention, in its broader aspect, contemplates switch operated mechanisms wherein the target rod and connecting rod are normally disassociated,

some of the following claims have been drawn so as not to be expressly limited to a structure wherein a single member is utilized for effecting both of these movements of the target body.

What I claim is:

1. In a railway switch point operating mechanism, the combination of a switch stand, a target rod slidable in said stand, a connecting rod attached to one of said switch points, and an operating lever for reciprocating said target rod to connect and disconnect the same from said connecting rod and for rotating said target rod to throw the switch when said target rod is connected to the connecting rod. 70 75

2. In a railway switch point operating mechanism, the combination of a switch stand, a connecting rod, a target rod normally disengaged from said connecting rod, said target rod being slidable in the switch stand to engage said connecting rod, and means for rotating said target rod to throw the switch when said rods are engaged with each other. 85

3. In a railway switch point operating mechanism, the combination of a connecting rod attached to said point, a switch stand, a rotatable block on said stand, a target rod slidable in said stand and block and normally disengaged from said connecting rod, and an operating lever pivoted in said block for reciprocating said target rod to move it into engagement with said connecting rod and for throwing the switch when said rods are engaged. 90 95 100

4. In a railway switch point operating mechanism, the combination of a connecting rod, a switch stand, a target rod slidable in said stand and normally disengaged from said connecting rod, and an operating lever pivoted on said stand and adapted to assume a depending position when said rods are disengaged and movable to a horizontal position to move the target rod into engagement with the connecting rod, said lever being locked against rotation when in its depending position and rotatable together with the target rod when in its horizontal position to throw the switch point. 105 110 115

5. In a railway switch point operating mechanism, the combination of a switch stand, a target rod supported in said stand, a connecting rod attached at one end to the switch points, said target rod and connecting rod being normally disengaged from one another, and means for moving said rods into engagement with each other preparatory to operation of the switch points. 120 125

6. In a railway switch point operating mechanism, the combination of a switch stand, a target rod supported in said stand, a connecting rod attached to said switch point but normally disengaged from said target rod, means for locking said connect- 130

ing rod against movement, and means for moving the target rod into engagement with the connecting rod preparatory to actuation of the switch points.

5. 7. In a railway switch point mechanism, the combination of head blocks, a connecting rod attached to said switch points and slidably between said head blocks, a switch stand mounted on said head blocks, a target rod supported in said switch stand, but normally detached from the connecting rod, and means for bringing said rods into engagement with each other preparatory to actuation of the switch points.

15. 8. In a railway switch point operating mechanism, the combination of a pair of head blocks, a connecting rod attached to the switch points and slidably supported between said head blocks and below the upper surface of said blocks, a switch stand mounted on said blocks, a target rod supported by said switch stand, but normally disengaged from the connecting rod, means for moving the target rod into engagement

25. with the connecting rod preparatory to actu-

ation of the switch points, and means for locking said connecting rod against actuation when disconnected from the target rod.

9. In a railway switch point operating mechanism, the combination of a pair of 30 head blocks, a plate spanning said head blocks, and having a chamber on its inner surface adapted to be positioned below the upper surface of the head blocks, a connecting rod attached at one end to the switch 35 points and having its other end slidably supported in said chamber, a switch stand mounted on said head blocks, a target rod supported in said stand, but normally disengaged from said connecting rod, means for 40 moving said target rod into engagement with the connecting rod preparatory to actuation of the switch points, a lever pivoted on said plate engageable with said connecting rod for holding the same against reciprocation, 45 and means for locking said lever in position to hold the connecting rod against reciprocation.

EUGENE F. SALISBURY.
